ATTORNEY

UNITED STATES PATENT OFFICE.

FRANCIS DONALD HOLDEN BRENNER, OF LONDON, ENGLAND, ASSIGNOR TO THE ENGLISH ELECTRIC COMPANY LIMITED, OF LONDON, ENGLAND, A BRITISH COMPANY.

BLOW-OUT ARRANGEMENT FOR ELECTRIC SWITCHES.

Application filed August 19, 1925, Serial No. 51,202, and in Great Britain September 12, 1924.

There are many cases where an electric switch has to break a current of considerable magnitude in a location where it is difficult to provide the space necessary for drawing out and extinguishing the arc. These conditions arise more particularly where a number of such switches have to be grouped together as, for example, in the case of multiple unit traction equipment using motor coaches where it is usual to mount the switches controlling the motor circuits of each coach in the space beneath the floor of the coach. In this instance, the total available space is limited and in addition to that it is desirable for convenience of actuation to group the switches as close together as possible.

The present invention deals with the difficulty above indicated and consists in providing that the principal part of the drawing out and extinguishing of the arc is performed by an auxiliary switch which can be located at a reasonable distance away from the main circuit breaking device and is brought into circuit by the small arc produced at the contacts of the main circuit breaking device.

The invention will now be described by way of example with reference to the accompanying diagrammatic drawings of which Figure 1 shows in elevation the contacts and arc destroying arrangement of a main switch one side of the arc chute being removed and Figure 2 shows on the left side a part sectional plan on the line II-II of Figure 1 and on the right side a part plan. Figure 3 shows in elevation portions of an auxiliary switch, including the contacts and the arc destroying arrangement, one side of the arc chute being removed, and Figure 4 shows a section on the line IV-IV of Figure 3. Figures 5 and 6 show views similar to those shown in Figures 3 and 4 of a modified construction of an auxiliary switch and Figure 6 is a section on the line VI-VI of Figure 5. Figure 7 shows a diagram of connections for two main switches and an auxiliary switch. The main switch (Figures 1 and 2) is arranged with arc horns 1 and 2 in a chute 3 and provided with blow out coil 4 and pole faces 5, but these members are of materially smaller dimensions than would be required if the

whole extinction of the arc which occurs upon opening contacts 6 and 7 were to be performed therein, since the energy to be dissipated within chute 3 each time the arc is broken is a comparatively small part of that present in the usual arrangement.

The main switch contacts 6 and 7 are shown in their closed positions into which they have been moved from the open position due to the energizing of coil 27 of solenoid 31 which consequently lifts its armature 32 and communicates this motion to the moving contact 6 by way of connecting rod 47 and member 16 which is pivotally connected at 28 to a fixed conducting member 34. As soon as the coil 27 is de-energized the armature 32 will fall (assisted by a biasing force such as a spring if required) and will cause the moving contact 6 to move to the left. Current enters the main switch at terminal 35 and passes through the winding of the blow-out coil 4 to the conducting member 34 to which the horn 1 is conductively fixed. The current then passes to the moving and fixed switch contacts 6 and 7 and to the fixed conducting member 29, to which the horn 2 is conductively fixed, and out at the terminal 30.

To establish connection with the auxiliary switch additional horns or electrodes 8 and 9 are arranged between the usual arc horns 1 and 2 in chute 3 of the main switch, but in some instances one additional horn only may be used. Where two electrodes are employed the circuit to the auxiliary switch will be quite independent of the main circuit, except when an arc exists, but where a single electrode is used one of the horns 1 and 2 of the main switch will be permanently connected with a contact of the auxiliary switch. Electrodes 8 and 9 are preferably arranged with a barrier 10 of insulating material, for instance soapstone, placed between them, and projecting as at 11 from their inner ends, so as to draw out the arc of the main switch between them. Electrode 8 is electrically connected through the cable 20 with one contact of the auxiliary switch, and electrode 9 is electrically connected through cable 36 with the other contact of the auxiliary switch, and the contacts 12 and 13 of the auxiliary switch Figures 3 and 4 are normally closed, so that the establishment

of the circuit through them by the arc is accompanied by the extinction of that portion of the arc which is bridged by the circuit including the contacts of the auxiliary switch.

The auxiliary switch shown in Figures 3 and 4 is so arranged that as soon as current passes through it the contacts 12 and 13 are separated, thus producing an arc which 10 strikes onto horns 14 and 15, and travels outwards on them until it is extinguished, this action being assisted by a powerful magnetic blow-out. It is obvious that the extinction of the arc at the auxiliary switch is accompanied by the extinction of the partial arc or arcs at the main switch.

The cables 20 and 36 in Figure 1 are connected respectively to the terminal lugs 37 and 38 in Figure 3 so that current passes 20 from the additional electrode 8 in Figure 1 through the coil 17 of the blow-out device in Figure 3 to lever 24, moving and fixed contacts 12 and 13, terminal 38 and back by way of cable 36 to the additional electrode 9 in Figure 1. The arcing horn 14 is conductively connected through the member 33 to the inner end of the coil 17 and the other horn 15 is conductively connected to the fixed contact 13 and the terminal lug 38. In Figures 3 and 4 the current passing 30 through the blow-out coil 17 is utilized not only to energize the core 18 and cheeks 19 of the blow-out magnet for the arc between contacts 12 and 13 but also for attracting an armature to operate the switch. This 40 operation is carried out by providing on the iron circuit of the blow-out magnet a projection or preferably a pair of projections 21 through which passes a small leakage field in which is located an armature 22, coupled by nonmagnetic spindle 23 to lever 24, on which is mounted moving contact 12 of the auxiliary switch. Armature 22 will usually be kept of small dimensions 50 so as to restrict the leakage field. In order to assist in producing the rapid and certain opening of the auxiliary switch the connection between contact 12 and armature 22 may include a pin and slot connection or 60 equivalent free motion device. For instance spindle 23 may be formed with slot 25 through which passes lever 24 which is pivoted at 26, so that armature 22 moves an appreciable distance before giving movement to lever 24, and the armature has attained considerable velocity and reached a 70 strong part of the attracting field before spindle 23 contacts with lever 24 and starts rotating it about point 26 to open contacts 12 and 13.

The auxiliary switch shown in Figures 5 and 6 differs from that shown in Figures 3 and 4 in being provided with a blow-out coil which is energized from a source distinct from the current which has to be

interrupted. This coil is denoted by the numeral 39 and its terminals 40 and 41 are connected to some suitable source of current. The current to be interrupted passes from the cable 20 (Figure 1) to the terminal 42, 70 through the coil 43 of a solenoid device for operating the moving contact 12, to the lever 24 connected to that contact and thence to the fixed contact 13 and to terminal 44 which is connected to the cable 36 in Figure 75 1. The energization of the coil 43 causes the armature 45 of the solenoid device to rise together with the stud 46 to which it is connected. This stud then hits the lever 24 which rises and takes with it the contact 12 and so opens the contacts 12 and 13 of this auxiliary switch. The arcing horn 14 is conductively connected to the contact 12 by way of the lever 24 and the horn 15 is conductively connected to the fixed contact 80 12. The magnetic cheeks 19 are associated with the blow-out coil in the usual manner.

It will be seen that in many cases where a number of main switches are grouped together, but not intended to be opened simultaneously, a single auxiliary switch can be used in conjunction with them, the additional electrodes being connected in parallel. Fig. 3 shows two main switches 47 and 48 (which may be similar to Figure 90 1) each of which has its additional electrode 8 connected through blow-out and operating coil 17 of an auxiliary switch (which may be similar to Figure 3) to its moving contact 12 whilst electrodes 9 are 100 connected to stationary contact 13.

The invention is not limited to the precise arrangements shown in the drawings which are susceptible to many modifications. Obviously, where a single auxiliary switch 105 serves a large number of main switches which are being continually brought into action for opening the circuit, it may be advantageous to have the auxiliary blow out continuously energized as for example 110 in Figure 5. In this case, some independent means of opening the auxiliary switch must be provided, such, for instance as a separate series electrode-magnetic device (as for example in Figure 5) or a device utilizing 115 the electro-dynamic action of the field produced by the blow out coil upon a conductor carrying the current which flows to the auxiliary switch.

What I claim as my invention and desire 120 to secure by Letters Patent is:—

1. A blow out device comprising a main circuit breaking device, an auxiliary switch separate from the said main circuit breaking device, conducting means for carrying arc 125 current between the main circuit breaking device and the auxiliary switch, said means being adapted to be brought into circuit by an arc at the main circuit breaking device which is initiated by the normal functioning 130

of said device when commencing to open the circuit, and means associated with the auxiliary switch for stopping the flow of arc current therethrough.

- 5 2. A blow out device comprising a main circuit breaking device, an auxiliary switch, means for blowing out an arc at said auxiliary switch and means for connecting said auxiliary switch in series with the main circuit 10 cut breaking device by way of an arc at the main circuit device which is initiated by the normal functioning of said device in commencing to open the circuit.

- 15 3. A blow out device comprising a main circuit breaking device adapted to produce an arc when commencing to break the circuit, means for breaking an arc at said circuit breaking device, an auxiliary switch, means for blowing out an arc at said auxiliary switch, means for connecting said auxiliary switch in circuit with the main circuit breaking device by way of the said arc breaking means so as to bridge the break produced in the arc thereby.

- 25 4. A blow out device comprising a main circuit breaking device adapted to produce an arc when commencing to break the circuit, an electrode lying in the path of the arc produced at said circuit breaking device, an auxiliary switch, means for blowing out an arc at said auxiliary switch and means for connecting said auxiliary switch in circuit with said main circuit breaking device by way of said electrode.

- 35 5. A blow out device comprising a main circuit breaking device, arcing horns on the main circuit breaking device between which an arc is established by the normal functioning of said device when commencing to break 40 the circuit, two electrodes arranged between the arcing horns, an insulating barrier placed between the electrodes and projecting beyond their inner ends, an auxiliary switch, means for conveying arc current between the 45 said electrodes and the auxiliary switch, and means associated with the auxiliary switch

for stopping the flow of arc current therethrough.

6. A blow out device comprising a main circuit breaking device adapted to establish an arc when commencing to break the circuit, an auxiliary switch separate from the main circuit breaking device, means for conducting arc current between the main circuit breaking device and the auxiliary switch, 55 and combined means for opening the contacts and blowing out the arc of the auxiliary switch upon the flow of arc current therethrough.

7. A blow out device comprising a main circuit breaking device adapted to establish an arc when commencing to break the circuit, an auxiliary switch, means for conveying arc current between the main circuit breaking device and the auxiliary switch, a 60 blow out magnet on the auxiliary switch, an armature adapted to be influenced by the blow out magnet and opening means acting on a contact of the auxiliary switch and actuated by the said armature.

70 8. A blow out device comprising a plurality of main circuit breaking devices, each one of which is adapted to establish an arc when commencing to open its circuit, a single auxiliary switch, means for conducting arc 75 current between each main circuit breaking device and the auxiliary switch, and means associated with the auxiliary switch for stopping the flow of arc current therethrough.

9. A blow out device comprising a main circuit breaking device adapted to establish an arc when commencing to open the circuit, an auxiliary switch, means for conducting arc current between the main circuit breaking device and the auxiliary switch, 80 means including a coil influenced by arc current for opening the auxiliary switch and a blow out coil on the auxiliary switch, which coil is energized by current from a separate source of supply.

In testimony whereof I affix my signature.

F. D. H. BREMNER.
